MOBILE HOT FOOD AND HEATED DISH CARRIER

William H. Frick, 850 Euclid Ave., Cleveland, Ohio

Filed Oct. 11, 1957, Ser. No. 48,061

Term of patent 14 years

(Cl. D14—3)

FIG. 1

FIG. 2

FIG. 3

Fig. 1 is a top plan view of a mobile hot food and heated dish carrier showing my new design;

Fig. 2 is a front elevational view thereof;

Fig. 3 is a side elevational view thereof; and

Fig. 4 is a rear elevational view thereof.

I claim:

The ornamental design for a mobile hot food and heated dish carrier, as shown and described.
